WRAP STRIPE MECHANISM FOR KNITTING MACHINES

Howard Grady Dickens, Thomasville, N. C., assignor to Ragan Knitting Company, Thomasville, N. C., a corporation of North Carolina

Application January 2, 1940, Serial No. 312,001

11 Claims. (Cl. 66—135)

This invention relates to a knitting machine and more especially to an apparatus for producing a seamless hose, having lengthwise stripes or clocks therein. These stripes are usually knitted in the hose by introducing strands of wrap yarn to spaced selected needles while the body yarn is being knitted; or if desired, the wrap yarn can be knitted in spaced wales and floated over the intermediate wales so as to produce a different external appearance from the stripes or clocks, in the manner such as disclosed in the patent to Lawson, Number 1,872,760 of August 23, 1932.

Heretofore, it has been the common practice to produce a hose with wrap stripes therein by means of a circular knitting machine with the wrap yarn feeding mechanism disposed above the needle circle. In some forms, the wrap yarn feeding mechanism is mounted rotatably on an axis within the needle cylinder which is parallel and eccentric to the axis of the cylinder, and both the feeding mechanism and the cylinder are adapted to rotate at the same revolutions per minute; however, due to the fact that the diameter of the needle cylinder is much greater than that of the feeding means, the rate of travel of the needles is much greater than the rate of travel of the feeding means at the point of introduction. As a result, it is possible to elevate certain groups of needles so that the hooks on the upper ends thereof will engage a particular wrap strand and knit the same in the stocking, only where these needles occur. Nevertheless, by having the wrap yarn feeding mechanism on an axis, parallel and eccentric to the axis of the needle cylinder and within the needle circle, much difficulty is encountered when inspecting the parts of the needle cylinder, as well as when inspecting the hose while it is being knitted. In other words, the wrap yarn attachment obstructs the view of the cylinder needles and also prevents these parts from being easily accessible.

It is therefore an object of this invention to provide a wrap yarn attachment to be used in combination with a knitting machine, said attachment being positioned relative to the needle cylinder in such a manner that it will not obstruct the view to the top of the needle cylinder and so that quick access to the fabric and adjacent parts can be had.

It is another object of the invention to provide a wrap yarn feeding mechanism so positioned that the wrap yarns do not have to be guarded from contact with the plate which supports the clamp and cutter for the main yarn, thereby preventing chafing of the wrap yarns.

Some of the objects of the invention having been stated, other objects will appear as the de-

scription proceeds when taken in connection with the accompanying drawings, in which—

Figure 1 is a plan view of the improved knitting machine and striping attachment, with certain portions of said attachment being shown in section;

Figure 2 is a side elevation of the machine looking at the left-hand portion of Figure 1, showing the thrust bar for actuating the body yarn feeding mechanism, and the thrust bar for actuating the slide wire or wrap yarn tension control for the wrap yarn stitch;

Figure 3 is a view similar to the lower left-hand portion of Figure 2 showing cam means on the main drive for actuating the thrust bar which controls the introduction and withdrawal of the body yarn;

Figure 4 is a vertical sectional view taken along the line 4—4 in Figure 1 showing the cam means on the main drum and the thrust bar for raising the wrap yarn at an elevation above the high needles when the heel and toe portions are being knitted, and also showing a portion of the thrust bar for controlling the body yarn cutter;

Figure 5 is a sectional view showing the cam means on the main drum for operating the body strand cutter mechanism when this strand is withdrawn;

Figure 6 is a sectional view through the main drum showing the cam means and thrust bar for introducing or withdrawing the double sole yarn, the upper end of said thrust bar being shown in Figure 1;

Figure 7 is a vertical sectional view taken along the line 7—7 in Figure 1;

Figure 8 is a vertical sectional view taken along the line 8—8 in Figure 1;

Figure 9 is a vertical sectional view similar to the central portion of Figure 7 but showing the position of the wrap strands as they pass beneath the cutter and clamp supporting plate;

Figure 10 is a schematic view showing the cam and needle arrangement employed in the knitting operations, and looking at the inside of the needle circle;

Figure 11 is a sectional view taken along the line 11—11 in Figure 10;

Figure 12 is a perspective view of the gap closing ring shown in association with the wire for raising the wrap strands above the high needles when the heel and toe portions are being knitted;

Figure 13 is a perspective view of the horn and tension control wire which are adapted to be disposed within the gap closing ring shown in Figure 12 and also within the needle circle when the parts are in assembled position;

Figure 14 is a perspective view of the upper end of the yarn tube showing guiding means

integral with the upper end thereof for holding the fabric and the attached wrap strands in the proper position when the wrap yarn is not being knitted;

Figure 15 is a view of a stocking made in accordance with the present invention.

Referring more specifically to the drawings, the numeral 10 denotes a hollow standard of conventional type which is adapted to support the needle cylinder of a knitting machine (Figures 2 and 7). Rotatably mounted upon the upper portion of this standard is a beveled gear 11, which gear is adapted to mesh with another beveled gear 12 on a main drive shaft 14. The gear 11 has integral therewith a vertically disposed tubular portion 15, around which conventional needle cylinder 16 is mounted, said cylinder having a plurality of radially disposed grooves 17 therein into which knitting needles 18, 19, 20 and 21 are adapted to be slidably mounted.

The needles 18 and 19 are identical in all respects except for the fact that the needles 18 have short butts and the needles 19 have long butts. Likewise the needles 20 and 21 are short and long butt needles, respectively, and are positioned at spaced intervals in the needle cylinder to take the wrap yarn. All of these needles are adapted to rest upon cam ring 22 when they are in the position shown in the extreme right hand portion of Figure 10. It will be noted that the needles 20 and 21 have short and long butt jacks 23 and 24, respectively, thereunder, said jacks being adapted to have their butts move in groove 25 in the lower portion of the cam ring 22. As the needles move to the left, they gradually approach an inclined portion 26 which serves to raise all of the needles to the same elevation, which is somewhat higher than the elevation of the needles in the extreme right hand portion of Figure 10. At the same time, the short butt jacks and long butt jacks 23 and 24, respectively, are moved to the left and the butts from these jacks ride upwardly on inclined surface 27 of movable cam 28. The incline of this cam surface is such as to force the needles 20 and 21 thereabove to a still higher elevation than that elevation to which the needles were forced by means of the inclined surface 26. The cam 28 is adapted to be moved toward and away from the center of the needle cylinder. When it is desired for the cam surface 27 to engage the butts of all of the jacks 23 and 24, the cam 28 is pushed inwardly the maximum amount as shown in Figure 11; whereas if it is desired to contact only the long butt jacks 24, the cam is withdrawn a sufficient amount to clear the short butts of the jacks 23, but at the same time, close enough to engage the extremities of the long butts of jacks 24. Likewise, if it is desired not to raise either of the needles 20 and 21, the movable cam 28 can be withdrawn still farther, where the butts of all the jacks will clear. This movable cam provides means whereby some of the stripes in the hose can be omitted while knitting part of the stocking, and all of them can be put in at another point in the course of knitting the stocking.

After passing the movable cam 28, the elevated needles 20 and 21 which are disposed above the jacks 23 and 24 are adapted to have their butts contacted by a leveling cam 29 which lowers these needles to an elevation where their butts will contact right-hand stitch cam 40. From the cam 40 the butts of all of the needles move in

contact with cams 41 and 42 which deliver them to normal knitting position.

When the needles which are disposed above jacks 23 and 24 have been raised to elevated position by the cam 28, the hooks on the upper ends thereof are in a position to engage strands 36 of wrap yarn, which strands emanate from ports or holes 37 in a rotating disk 38. Disk 38 is mounted upon a suitable shaft 39, which shaft 10 is adapted to rotate in a clockwise manner in Figures 4 and 10. Although the revolutions per minute of the needle cylinder 16 is the same as that of the disk 38, the rate of travel of the needles within this cylinder is much greater than the rate of travel of the ports 37 in the disk 38 on account of the difference in diameter of the needle circle and disk 38; consequently the elevated needles which are disposed above jacks 23 and 24 will engage the lowermost strand 36 at a point slightly below the hooks and cause the strand to be knitted into the stocking by these needles when the needles advance to the knitting point. The low needles whose hooks do not engage this strand will not knit it.

It should be borne in mind that the conventional body yarn of the stocking is introduced at a point between the disk 38 and the stitch cam 42. In other words, the conventional yarn feeding means is disposed at a point directly above the cam 41 (see Figures 2 and 10).

A conventional sinker ring 45 is adapted to be supported near the top of the needle cylinder 16, said sinker ring having conventional sinkers 46 therein which sinkers are disposed between the needles. The sinkers are adapted to engage the loops of the fabric, such as a stocking 47 while it is being knitted.

By observing Figure 1, it will be seen that the sinker ring 45 has spaced projections 48 and 49 near the front side thereof in which bolts 50 and 51 are adapted to be threadably secured. The proximate ends of these bolts are disposed upon opposed sides of a post 52 with the conventional clearance, which post extends upwardly from a table member 53 therebelow. Member 53 also supports another post 54 which extends upwardly and has pivoted to the upper end thereof as at 55, a latch ring 56, and this latch ring is adapted to be latched in position to the upper end of the post 52 by any suitable means such as a spring latch 57.

Pivotedly secured to the latch ring 56 as at 58, are body yarn feed finger 59 and double sole strand feed finger 60. These fingers are adapted to have strands 61 and 62 respectively pass therethrough, and be fed to all of the needles 18 therebelow at a point slightly in advance of the stitch cam 42 (see Figure 10).

Body yarn feeding mechanism

The body yarn 61 is introduced and withdrawn by means of finger 59, said finger being adapted to be raised or lowered by means of a vertically disposed thrust bar 65 resting upon a main drum 66 in the manner shown in Figure 3. This drum has cams 67 and 68 thereon, said cams being so positioned upon the drum as to provide low places 69 and 70 therebetween. When the lower end of the thrust bar 65 is in the position shown on the main drum in Figure 3, the machine is knitting in high heel portion 72 of the stocking 47 (see Figure 15). When this high heel portion is being knitted by body yarn 61, the reinforcing yarn 62 is also being introduced for a part of each course at the beginning of heel portion 73; however, the end of cam 67 contacts

the thrust bar 65 thereby raising the body yarn away from the needles so that it will not be knitted. Of course at this time a suitable conventional heel yarn 63 will be introduced by a finger 64 (Figure 1) in a well known manner such as described in connection with finger 59, so that the heel portion 73 will be knit. After the heel has been knitted the cam 67 rides out from beneath the thrust bar 65, and the body yarn 61 and double sole yarn 62 are again introduced, at which time double sole foot portion 74 (Figure 15) is being knitted. When the blank space 69 has been traversed, the foot portion 74 is completed and at that time, the thrust bar 65 will ride upon the cam 68 to withdraw the body yarn. The double sole yarn will be withdrawn by mechanism to be later described. Then the finger 64 will again be actuated by a mechanism such as described in connection with finger 59 to again introduce yarn 63 while toe portion 76 is knitted. The thrust bar 65 continues to ride on the cam 68 until top 77 of the next succeeding stocking is knitted, at which time the bar 65 will fall off cam 68 onto the low space 70 and remain on this space until leg portion 78 is knitted.

Double sole yarn feeding mechanism

The mechanism which is employed for feeding the reinforcing strand 62 during knitting of the high heel portion 72 and foot portion 74 of the stocking, is shown in Figures 1 and 6. It is seen in Figure 1 that a thrust bar 80 is adapted to engage the lower intermediate portion of strand feed finger 62 and the lower end of this bar is adapted to be disposed above the main drum 66 in Figure 6. The main drum 66 has cams 82 and 83 on its periphery, these cams being so spaced as to provide intermediate low places 84 and 85. As the drum 66 rotates in a clockwise manner in Figure 6, the thrust bar 80 is adapted to be raised or lowered to thereby raise or lower the double sole yarn feed finger 60 at the proper time. For example, when the thrust bar is in the position shown in Figure 6 or upon the low place 84, the yarn feed finger 60 is in lowered position and feeding the reinforcing strand 62 to the needles as the high heel portion 72 of stocking 47 is being knitted. Of course, when the cam 82 rides beneath the lower end of the thrust bar 80, the double sole yarn is withdrawn, after which the heel portion 73 is knit by a conventional yarn feeding mechanism. After bar 80 drops off the cam 82 the double sole strand 62 is again introduced while the machine is knitting the double sole foot portion 74 and then as the cam 83 rides beneath the thrust bar 80 the yarn is again withdrawn and then the toe portion 76 and the top portion 77 of the next succeeding stocking is knitted.

Yarn cutting apparatus

It will be noted by referring to Figures 1 and 2 that the latch ring 56 has a suitable bracket 81 secured thereto by any suitable means such as screws 83. This bracket has one end thereof cantilevered over the latch ring and toward the central portion thereof. At the central portion of the latch ring a downwardly extending stud 89 projects from bracket 81, said stud being adapted to support a plate 90 on the lower end thereof. This plate is disposed a slight distance above the top of the sinkers and is employed for supporting clamps 92 and 93 and cutter 94, said cutter 94 being pivoted as at 95 directly above the

plate 90 (Figures 1 and 7). The cutter also has secured to one end thereof, a vertically disposed operating link 96 and the upper end of this link is secured to the free end of a horizontally disposed lever 97. Lever 97 is pivoted intermediate its ends as at 98 (Figure 4) and is adapted to be normally rotated in a counterclockwise manner in this figure by means of a suitable tension spring 99 to hold the cutter in closed position.

10 The other end of the lever 97 is adapted to be contacted by the upper end of a thrust bar 100, said thrust bar extending downwardly and having its lower end disposed directly above main drum 66 in the manner shown in Figure 5. The reinforced high heel portion 72 is being knit when the bar is in the position shown in Figure 5. The drum 66 has cams 102, 103, 104, 105, 106 and 107 spaced thereon at the proper locations. When the drum rotates so as to advance the cam 102 past the thrust bar 100 the cutters 94 are actuated to clip the body yarn as it is being withdrawn at the beginning of the knitting of the heel portion 73. As the drum continues to advance and the cam 103 passes the thrust bar, the heel yarn 73 is withdrawn and consequently the cutter 94 must operate to clip the heel yarn after it has been withdrawn. At this time, the double sole yarn 62 and body yarn 61 are again introduced and remain in knitting position until the cam 104 moves past the thrust bar at which time the strands 61 and 62 are withdrawn and clipped. In the meantime, the strand 63 is introduced for knitting the toe portion 76. The cam 105 serves to clip the withdrawn toe yarn 63 at the beginning of a suitable make up knitted area, not shown, which is disposed between the stockings as they are successively knitted, to serve as a tie. This make up yarn usually comprises only a few courses and when it is withdrawn the cam 106 serves to operate the cutter to clip the make up yarn. The yarn that is used to knit the top portion 77 is then introduced. When the top portion 77 has been knitted, the cam 107 rides past the thrust bar 100 and serves to clip the top yarn just as the body yarn is introduced.

Striping attachment

As heretofore stated, in connection with Figure 10, the rotating disk 38 has a plurality of strands 36 of wrap yarn emanating therefrom, which strands are engaged by the high needles 20 and 21 at the feeding point and knitted into the stocking 47 to form stripes. It will be noted by observing Figures 7 and 15 that each of the strands 36 leads to a vertical stripe 110 in the stocking. The width of this stripe depends largely upon the number of high needles and the distance therebetween, which are allowed to engage the strands 36. It should be stated, however, that when these needles are lowered to knitting position that the strand 36 is engaged only by the high needles; consequently, after the knitting of the strand takes place, the wrap strand will be free to float around with the cylinder 16, one end of the strand being knitted in the stripe and the other portion of the strand extending back to the disk 38. In this manner the stripes 110 are placed in the stocking 47. The number of stripes employed in the stocking usually corresponds to the number of strands which are fed through ports 37 in disk 38 to the spaced sets of high needles. However, it might be stated that conventional means previously described in connection with Figure 10, are provided in the apparatus for causing some of the strands 36 to emanate

nate from these ports to be knitted while others are caused to be omitted during the knitting of a portion of a stocking. For example, the stripes 110 do not all extend the entire length of the stocking in Figure 15, but instead, one of the stripes shown extends entirely through both the leg and foot portion while the other two stripes are disposed in the leg portion only of the stocking.

The shaft 39, upon which the disk 38 is mounted (see Figures 1 and 7) is fixedly secured within a hub member 112, said hub member being rotatably mounted within bearing 113, which bearing has arcuate leg portions 115 extending laterally therefrom, said leg portions being secured as at 117 and 118 to the latch ring 56. Also secured to the shaft 39 is a yarn disk 120 by any suitable means such as angle member 121 and a set screw 122. This set screw penetrates a slot 123 in the outstanding leg of the angle member 121 (see Figure 7) and thereby provides means for adjusting the position of the shaft 39 axially, so as to cause the disk 38 and its thread ports 37 to be capable of adjustment relative to the latch ring 56. The latch ring 56 is cut away as at 56a to form a suitable notch for the reception of the ends of the rotating thread ports 37.

The thread disk 120 has a plurality of packages of wrap yarn 125 mounted thereon at spaced intervals. A wrap strand 36 is drawn from each of these packages which strand passes through a hole 126 in another disk 127, said disk 127 being also secured upon shaft 39 by any suitable means such as set screw 128. After passing through the hole 126, the strand 36 passes beneath a tension device 130 and then beneath a circular wire 131 and over the hook portion 132 of a wire 133. This wire is pivotally secured in a stud 135 which extends from the disk 127 and has a tension spring 136 normally rotating the portion 132 away from the face of disk 127 to thereby take up any excess slack in strand 36. After the strand passes over portion 132 it is drawn again through a port 137 in disk 127, from whence it passes into longitudinal bores 138 in hub 112, to ports 37. The end of shaft 39 is rotatably mounted in stud shaft 140, which shaft is adjustably secured in supporting member 141 by means of screw 142. When it is desired to raise the latch ring 56, together with the striping attachment, it is necessary to manipulate the latch 57 (Figures 1 and 2) as well as to loosen stud shaft 140 and then rotate the latch ring together with the assembly just described about the point 55. In order to produce this rotation, it will also be necessary to loosen the screw 142 so as to slide the stud shaft 140 to the right until the end of shaft 39 is free.

The hub 112 has fixedly secured therearound, a beveled gear 150 by any suitable means such as a set screw 151. The hub 112 likewise has a disk 120 previously described fixedly secured thereon by means of set screw 120a (Figure 1). Meshing with the lower side of the beveled gear 150 (see Figure 7) is a beveled pinion 153 on the upper end of a vertically disposed shaft 154, said shaft having its intermediate portion rotatably mounted in a bracket 155 and bed 53 of the knitting machine. The lower end of the shaft 154 has a pinion 156 fixedly secured thereon which meshes with another beveled gear 151 on the main shaft 14. It can be seen by referring to Figure 7 that shaft 14 forms a common driving means for both the cylinder and the striping attachment. In other words each time

the cylinder 16 makes a complete revolution, the disk 120 which supports the packages of wrap yarn 125 also makes a revolution, and thus the disk 38 through which the strands 36 of striping yarn pass is rotated in timed relation to the rotation of the cylinder 16.

Double sole cutter apparatus

The beveled gear 150 (Figure 8) has a stud 160 extending from the face thereof. This stud is adapted to assist in the operation of the double sole clipping apparatus, when the reinforced portions 72 and 74 of the stocking 47 are being knitted (Figure 15). Figures 1, 7 and 8 show the mechanism for performing this operation. It is here seen that the horizontal shaft 98 is rotatably mounted in an upstanding lug 159 which is an integral part of the latch ring 56. Fixedly secured to the end of shaft 98 is an L-shaped member 161, having a plate 162 secured to the end of its horizontal leg. Pivotally mounted as at 163 is a lever 164, one end of said lever extending to the right (Figure 8) and having a T-shaped arcuate cam surface 169 integral with the extreme right-hand end. A tension spring 170 normally tends to rotate the lever 164 in a counter-clockwise manner about point 163 (Figure 8) and against a stop 171. The normal position of this lever is shown in bold lines in Figure 8 and at this time the stud 160 in the beveled gear 150, can rotate without contacting the cam surface 169. The left hand end of this lever has a wire 173 extending laterally therefrom, which wire is adapted to rest upon the upper end of a thrust bar 174, said thrust bar extending downwardly and having its lower end disposed directly above main drum 66. The drum 66 has cams 176 and 177 secured thereon directly in the path of the lower end of the thrust bar 174 and these cams or projections are so spaced upon the drum as to provide blank spaces 178 and 179 therebetween. When the drum 66 rotates during a knitting operation, and when the cam 176 rides beneath the lower end of the thrust bar 174 the lever 164 is rotated in the clockwise manner about point 163 (Figure 8) a sufficient amount to cause the cam surface 169 on the right hand upper end thereof to be disposed within the path of stud 160. When the beveled gear 150 rotates to cause this stud to contact this cam surface, the right hand lower edge of the lever 164 will be moved downwardly against a laterally extending pin 180, which pin extends from the plate member 162. As the stud 160 continues to rotate with the beveled gear, the entire assembly, comprising lever 164, plate 162, L-shaped member 160, shaft 98 and lever 97 will be rotated a slight amount in a clockwise manner to dotted line position (Figures 4 and 8) to cause the cutter 94 to be opened, and of course immediately after the cutter is opened the double sole yarn will be drawn therein. Immediately after the yarn is drawn within the cutter, the stud 160 rides off the cam surface 169 to allow the cutter under the tension of spring 99 to be closed upon the withdrawn double sole strand 62 (Figure 7). As a result, the yarn will be clipped. It is therefore seen that for each revolution of the needle cylinder while the high heel portion 72 is being knitted, that the yarn cutter 95 will be actuated to clip the double sole yarn, as it is withdrawn from the stockings. Conventional means are employed for withdrawing the double sole yarn 62 for a portion of each course while the high heel and foot

portions 72 and 74 are being knitted. This means comprises a thrust bar 80, the upper end of which is disposed beneath feed finger 60 (Figure 4). The sinker ring 45 has a rotating ring 167 on its lower side, said ring having a cam surface 166 thereon which contacts projection 165 of the thrust bar upon each revolution. Upon making this contact, the feed finger 60 will be raised to withdraw the double sole strand 62 for a part of each course.

It is to be understood that the clipping attachment must be operated in timed relation to the double sole yarn feed finger 60 and the double sole strand 62, which is fed therethrough to the needles. While the thrust bar 174 (Figure 8) is riding on the top of cam 176, the high heel portion 72 is being knitted, but when it rides off this cam onto the blank space 178, the heel portion 73 is started, and consequently there will be no necessity for the cutter to be operated by the mechanism shown in Figure 8. However, when the double sole foot portion 74 is started, the cam 77 rides beneath the thrust bar 174 to cause the cutter to be put in action again in the same manner previously described.

Gap ring and strand tension control actuating mechanism

By referring to Figure 1, it will be seen that a gap 185 is provided in the latch ring 56 at the throat plate. This gap is provided for the reception of the yarn feed fingers and it must be closed while the heel and toe portions of the stocking are being knitted to keep the needle latches of the high needles from closing at this point and thereby dropping stitches. This gap closing ring is indicated by reference character 190, said ring being rotatably mounted within the latch ring 56. Figure 12 shows a perspective view of this latch ring. It is here seen that a notch 191 is provided in the far side thereof, which notch has steps 192 and 193 therein. It is through the notch 191 and upon the steps 192 and 193 that the wrap strands 36 are adapted to pass during the wrap strand feeding operation. The relative position of this notch 191 to the ports 37 and disk 38 is also clearly shown in Figures 4 and 10. While a strand 36 travels along step 192, it is disposed slightly above the hooks of the high needles 20 or 21, but when the strand is rotated to the step 193 it is at such an elevation that the hooks of the high needles can engage the same.

The gap ring 190 has a hole 195 therein which is engaged by one end of a link 196, said link having its other end pivotally secured to the upper end of a lever 198 (Figures 1 and 2). This lever 198 has its lower end pivoted as at 199 to standard 54. Integral with the lower portion of lever 198 is a laterally extending lug 200, and this lug normally rests directly above a projection 201 on vertically disposed thrust bar 202. The lower end of the thrust bar 202 is disposed directly above drum 66, which has cams 205 and 206 spaced thereon, within the path of the lower end of the thrust bar 202, said cams being so spaced as to leave low places 207 and 208 therebetween. Since it is necessary to rotate the gap closing ring 190 a substantial amount when the heel and toe portions are being knitted, so as to cause the gap 185 in the latch ring to be closed, it is necessary to provide the previously described mechanism indicated by the reference characters 196 to 208 inclusive. As the lower end of the thrust bar 202 rides upon the cam 205, the knitting of the heel por-

tion 73 is just begun, and as a result of this rise of the thrust bar, the lever 198 will be rotated a slight amount in a counter-clockwise manner in Figure 2 thereby pulling the link 196 to the left (Figure 2). This action will serve to rotate the gap closing ring 190 in a clockwise direction in Figures 1 and 12 to cause the gap 185 to be closed. When cam 206 rides beneath the thrust bar 202 a similar action takes place for the knitting of the toe.

Also during the knitting of the heel and toe portions 73 and 76, respectively, of the stocking, it is desirable to withdraw the tension control wire 210 to prevent its end from becoming entangled during the reciprocation of the needle cylinder. In other words, the wire has no function, except when the wrap yarn 36 is being knitted. This wire which is indicated by the reference character 210 is shown in Figures 1, 4, 7, 9 and 13. This wire is slidably mounted in a coiled spring 211, the combination of wire 210 and spring 211 being commonly known as a Bowden wire. The coiled spring 211 is secured to the exterior surface of an arcuate horn or plate 212, which has notches 213 and 214 therein, which substantially match the notches 192 and 193 in the gap closing ring 190.

The horn 212 is adapted to be located within the needle circle and is supported by an L-shaped member 215, which extends upwardly and then laterally, the lateral leg of this L-shaped member having a slot 217 and a hole 218 therein which are penetrated by screws 219 and 220 respectively (see Figure 1). These screws also are embedded in a laterally extending leaf 221 which is an integral part of one of the arcuate legs 115 (Figures 1 and 4). The purpose of providing the slot 217 is to facilitate the proper adjustment of the horn member 212 relative to the needle circle. The coiled wire 211 (see Figure 2) is clamped as at 230 to the upper end of lever 198, and the wire 210 which is slidably mounted within the coiled wire, is fixedly secured to this same lever as at 231. When it is desired to withdraw the projecting end of wire 210 into the coiled wire 211, that is so that it will not project out from the end of the horn during the knitting of the heel and toe, it is necessary to rotate the lever 198 in a counter-clockwise manner in Figure 2. Since this withdrawal takes place simultaneously with the closing of the gap 185, the same cams namely 205 and 206, previously described, can be used for this purpose. It should be stated that the function of this wire is to vary the amount of slack within the loops of the wrap yarn as these loops are being knitted.

Figure 7 shows a strand of wrap yarn 36 and its relation to the projecting tension control wire 210. It is here seen that the center strand 36 emanates from a port 37 and is disposed over the high portion 190a of the gap closing ring 190. It passes downwardly under the hooks of a pair of needles 21 which have been previously elevated to engage this strand at the notch 191. When the needle cylinder rotates the last named needles a slight distance farther to the left than shown in Figure 7, the strand 36 then passes over the end of wire 210, after which the needles 21 will be lowered to knit the wrap yarn 36 into the fabric, thereby forming a portion of the stripe 110. The longer the projecting length of the wire 210 beyond the end of horn 212, the greater will be the slack, that will be produced in the knitted wrap yarn. By varying the projecting length of wire 210 the degree of exposure

of the knitted stripe can be controlled. In order to normally return the gap closing plate 190 to normal position as shown in Figure 1, a suitable tension spring 235 is provided. This tension spring likewise serves to maintain the wire 210 in a projected position as shown in Figures 1, 7, 9 and 13.

Wrap yarn lifting mechanism

During the knitting of the heel and toe, it is necessary to elevate the wrapping strands 36, so that the same will not be engaged by high needles as they pass by the disk 38. This action is produced by an arcuate shaped wire 237 which has a vertically disposed leg 238 integral therewith, the upper end of which is secured to a lever 239 (Figures 4 and 12). The arcuate portion 237 is disposed between the horn 212 and the back of the needles. It is also positioned directly beneath the strands of warp yarn 36 and at a position adjacent the notches 192 and 193 in the gap closing ring 190 and the notches 213 and 214 in the horn 212. The lever 239 has a hole 240 therein which hole is penetrated by a screw 241 (see Figure 4). The screw 241 is secured to the free end of a lever 242 which, in turn, is pivotally secured as at 58 to the latch ring 56. The free end of the lever 242 has a laterally extending stop 244 integral with the upper portion thereof and positioned directly above the right hand end of the lever 239, said lever 238 being normally rotated in a counterclockwise manner about pivot point 241 against said stop by means of a spring 245. Also extending laterally from the lever 242 is a stud 246, the lower end of which is normally contacted by the upper end of a vertically disposed thrust bar 247, and the lower end of this thrust bar normally rests directly above the drum 66, which drum has at this location, a pair of cams 250 and 251 on its periphery. These cams are so spaced as to provide low places 252 and 253 therebetween. When the lower end of the thrust bar 247 rides upon the cam 250 during the knitting of the heel portion 73, of the stocking. The lever 242 together with the arcuate wire 237 is raised from the position shown in the drawings and to such an elevation that the strands 36 which emanate from the ports 37 will be raised sufficiently high so as to allow the high needles 20 and 21 to pass thereunder without engaging the same. Likewise when the thrust bar 247 rides upon the cam 251, the toe is being knitted and the strands 36 are again raised in the same manner as when the heel portion is knitted. When the thrust bar rests on the low places 252 and 253, the other portions of the stocking are being knitted and at that time the wire 237 is lowered along with the wrap strands 36 so as to be in a position for being engaged by the high needles 20 and 21 to be knitted into the stocking.

It is very desirable that the arcuate portion 237 remain substantially horizontal while it is being raised. In order to produce this result, it is necessary to pivotally secure this member to the lever 239 as at 241 as previously described. Also the vertical leg 238 is adapted to contact this projecting end of a plate 255 (see Figures 1 and 4). During the raising of the arcuate portion, it is necessary to rotate the lever 242 upwardly, but since the vertical leg 238 normally contacts the end of plate 255, this leg will be held in a substantially vertical position at all times. The plate 255 has a slot 257 therein which is penetrated by the screw 220 previously described. This slot is pro-

vided so that the proper adjustment of the plate can be effected relative to vertical leg 238.

Fabric tube guiding mechanism

When the wrap yarn 36 is not being knitted, it is necessary to hold the same in such a position that by raising selected needles slightly above their normal elevation at the feeding point the strand can be engaged. Of course, the wrap yarn continues to rotate around with the needle cylinder 16 when it is not knitted, at which time it merely floats beneath the plate 90 in the manner shown in Figures 7 and 9. In order that the wrap yarn may be sufficiently removed from the needles, it is necessary to provide a fabric support at a point adjacent the notch 191 in the gap closing ring 190 and adjacent notches 213 and 214 in horn 212. This supporting mechanism is clearly shown in Figures 7 and 14, and comprises a pair of wires 261 and 262 which are bent in a substantially inverted U-shaped manner with their ends secured to the upper end of a tubular member 263. The upper portions of these wires are adapted to be disposed directly beneath the knitted fabric to support the same at a point where the wrap strands are introduced. In other words, it can be seen by referring to Figure 7 that the fabric is held in a substantially horizontal position for a considerable distance from the needles at the point where the wrap strands are first engaged by the high needles 20 and 21.

This tubular member 263 is telescopically mounted in the upper end of a fabric tube 265, said tube extending downwardly within the needle cylinder and having integral with its lower end a vertically disposed rod 266. This rod is adjustably mounted in a stud 267 which extends inwardly from the interior of hollow standard 10. A set screw 268 is provided so that the height of the fabric tube 265 and its associated tubular member 263 in the upper end thereof can be varied.

It is therefore seen that a simple striping attachment has also been provided which can be mounted upon a knitting machine which attachment will not obstruct the visibility of the operating parts or interfere with the accessibility thereto. It also has a very desirable function in that the yarn will travel beneath the plate 90 and the clamping and cutting members 92 and 93 and 94 thereabove of its own accord without the necessity of any guiding mechanism.

In the drawings and specification, there has been set forth a preferred embodiment of the invention, and although specific terms are employed, they are used in a generic and descriptive sense only and not for purposes of limitation, the scope of the invention being set forth in the appended claims.

I claim:

1. A circular knitting machine having means for feeding a body yarn to the needles, a clamp and cutter for the body yarn mounted within the needle circle, means disposed outside the needle circle for feeding a plurality of wrap yarns to selected needles, and means for engaging the wrap yarns and raising them out of the path of the needles during reciprocatory knitting.

2. In a circular knitting machine having a throat plate provided with yarn feed fingers and also having a clamp and cutter disposed within the needle circle, rotary means disposed at all times wholly outside the projected needle circle and in advance of the throat plate for feeding a plurality of wrap yarns to selected needles at

a point low enough to pass in a straight line below the clamp and cutter between the point where the wrap yarns are knitted in the fabric and the point of feeding, and means for raising the wrap yarns during reciprocatory knitting.

3. In a circular knitting machine having a clamp and cutter disposed within the needle circle, means for feeding a main knitting yarn to the needles, rotary means disposed at all times wholly outside the projected needle circle and in advance of the point where the main knitting yarn is fed for feeding a plurality of wrap yarns to selected needles, the wrap yarns being fed at a point outside the needle circle sufficiently low to travel in a straight line from the feeding means to the fabric as it revolves so that it passes unassisted beneath the clamp and cutter, and means for raising the wrap yarns during reciprocatory knitting.

4. In a circular knitting machine having means for feeding a main knitting yarn to the needles, and having a clamp and cutter for the main yarn disposed inside the needle circle, a member mounted in advance of the main yarn feeding means for rotation on an axis at substantially a right angle to the axis of the needle circle, feeding means carried by the member and having feed eyes disposed at all times outside the projected cylinder defined by the needles for passing successively a plurality of wrap yarns into contact with selected needles of the knitting machine, the feeding means being disposed low enough so that the wrap yarns will pass unassisted beneath the clamp and cutter while defining a straight line between the feeding means and the point where the wrap yarns are knitted into the fabric, and means for raising the wrap yarns during reciprocatory knitting.

5. A circular knitting machine having a plurality of needles arranged in a circle and having means for feeding a main knitting yarn, a heel and toe yarn and a double sole yarn to the needles and also having a clamp and cutter for said yarns arranged within the needle circle, rotary means disposed outside the circle and having feed eyes disposed at all times outside the projected cylinder defined by the needles for feeding a plurality of wrap yarns to selected needles at a point low enough so that the wrap yarns as they move with the fabric being knitted will pass unguided beneath the clamp and cutter, and means for raising the wrap yarns during reciprocatory knitting.

6. A circular knitting machine having a plurality of needles arranged in a circle and having means for feeding a main knitting yarn, a heel and toe yarn and a double sole yarn to the needles and also having a clamp and cutter for said yarns arranged within the needle circle, means disposed outside the circle for feeding a plurality of wrap yarns to selected needles at a point low enough so that the wrap yarns as they move with the fabric being knitted will pass unguided beneath the clamp and cutter, and means for raising the wrap yarns during reciprocatory knitting.

7. A circular knitting machine having a plurality of needles arranged in a circle and having means for feeding a main knitting yarn, a heel and toe yarn, and a double sole yarn to the needles and also having a clamp and cutter for said yarns arranged within the needle circle, means disposed outside the circle for feeding a plurality of wrap yarns to selected needles at a point low enough so that the wrap yarns as they move with the fabric being knitted will pass

unguided beneath the clamp and cutter, and means for supporting the fabric being knitted to prevent the wrap yarns from pulling it into contact with the needles as they pass the wrap yarn feeding means.

8. A circular knitting machine having a plurality of needles arranged in a circle and having means for feeding a main knitting yarn, a heel and toe yarn, and a double sole yarn to the needles and also having a clamp and cutter for said yarns arranged within the needle circle, means disposed outside the circle for feeding a plurality of wrap yarns to selected needles at a point low enough so that the wrap yarns as they move with the fabric being knitted will pass unguided beneath the clamp and cutter, means for raising the wrap yarns during reciprocatory knitting, and means for supporting the fabric being knitted to prevent the wrap yarns from pulling it into contact with the needles as they pass the wrap yarn feeding means.

9. In a knitting machine having means for feeding a regular yarn, means disposed substantially a quarter circle in advance of the regular yarn feeding means and all portions of which are at all times outside the projected needle circle for feeding a striping yarn, a rotatable needle cylinder having a circle of needles, a clamp and cutter plate disposed within the needle circle, means for elevating all of said needles to the same elevation as the cylinder rotates, additional means for elevating spaced selected needles to a still higher elevation into the path of the striping yarn, said striping yarn feed means being disposed at a right angle to the axis of said cylinder whereby the yarn emanating therefrom will traverse the path of said needles raised to a still higher elevation, the point of feeding of the striping yarn being low enough so that the striping yarn will pass unguided beneath the clamp and cutter plate and will not interfere with the clamp and cutter disposed thereon.

10. A circular knitting machine comprising in combination, a circular series of needles, a plate supported within the circle of needles and having a yarn cutter and clamp mechanism for the main knitting yarn, means for introducing the main knitting yarn, means disposed at all times outside the projected needle circle and in advance of the means for introducing the main knitting yarn for presenting one or more lap threads to selected needles to produce lap stripes, the point of feeding the lap threads being low enough so that they will pass unguided beneath the plate and will not interfere with the cutter and clamp mechanism.

11. In a circular knitting machine having means for feeding a main knitting yarn to the needles, and having a clamp and cutter for the main yarn, a member mounted for rotation on an axis at an angle to the axis of the needle circle, feeding means carried by the member for passing successively a plurality of wrap yarns into contact with selected needles of the knitting machine, the feeding means being disposed low enough so that the wrap yarns will pass unassisted beneath the clamp and cutter while defining a straight line between the feeding means and the point where the wrap yarns are knitted into the fabric, said feeding means being at all times outside the projected needle circle and being located approximately 90 degrees in advance of the means for feeding the main knitting yarn.
